(57) **CLAIM**

The ornamental design for a buffet, as shown and described.

DESCRIPTION

FIG. 1 is a left front perspective view of a buffet showing my
new design;

FIG. 2 is a side view, the opposite side being a mirror image
thereof;

FIG. 3 is a front elevational view thereof; and,

FIG. 4 is a top view thereof.

The bottom and rear elevational views of the design are not
shown and form no part of the claimed design. The dashed
lines represent environmental elements only and form no
part of the claimed design.
